Patented Apr. 13, 1920.

Inventor
Frank Kutwicz

By William C. Linton

Attorney

UNITED STATES PATENT OFFICE.

FRANK KUTWICZ, OF REGINA, SASKATCHEWAN, CANADA.

COLLAPSIBLE CANE.

1,336,638.

Specification of Letters Patent. Patented Apr. 13, 1920.

Application filed March 8, 1919. Serial No. 281,451.

To all whom it may concern:

Be it known that I, FRANK KUTWICZ, a citizen of the Republic of Poland, residing at Regina, Province of Saskatchewan, 5 Canada, have invented certain new and useful Improvements in Collapsible Canes; and I do hereby declare that the following is a full, clear, and exact description of the invention, such as will enable others skilled 10 in the art to which it appertains to make and use the same.

The present invention relates to canes and similar walking sticks, and an object of the present invention is to provide a cane of 15 this character which can be easily and readily folded in a compact package, whereby when the same is not in use it may be placed within a small package or the pocket of the user. A further object of the present invention is to provide a folding cane consisting of a plurality of folding parts, which when in an open position will establish a single rigid section so that it may be used as a walking stick.

25 With the above and other objects in view which will hereinafter appear as the description continues, the invention consists of the novel features of construction, combination and formation of parts as will be 30 hereinafter more fully described and particularly pointed out in the appended claim.

In the accompanying drawings has been shown a simple and preferred form of the invention, it being, however, understood that 35 no limitation is necessarily made to the precise structural details herein exhibited, but the right is hereby reserved to any changes, alterations or modifications to which recourse may be had that come within the 40 scope of the claim without departing from the spirit of the invention or sacrificing the efficiency of the same.

In the accompanying drawings: Figure 1 is a side elevation of the cane embodied 45 in the present invention when in open or extended position; Fig. 2 is a perspective view of the cane when in folded position. Fig. 3 is an enlarged detail longitudinal section of one of the connecting hinges of the 50 sections; and, Fig. 4 is a detail section taken at right angles to Fig. 3.

55 Referring now more particularly to the accompanying drawings wherein like and corresponding parts are designated by similar reference characters throughout the several views.

The cane embodied in the present invention comprises a plurality of sections 1 which are preferably six in number as shown. These sections are each of the same length 60 but have a tapered outer configuration so as to give the desired taper for a cane when they are in open or extended position. The opposite ends of each section are square so that they may rest one upon the other and 65 form a close connection. Countersunk within the ends of each section are hinges and the hinges indicated by the numeral 2 are arranged at one side of the cane when in extended position, whereas the hinges 3 70 are arranged at one side of the sections or at right angles to the hinges 2. Extending from the medial portion of one side of each section is a blade 4 and these blades 4 are adapted to rest within the slots 5 formed 75 within the opposite end of the adjacent sections. One edge of each of these blades is cut away as at 6 so that they will enter the slots 5 freely. Countersunk within one face of each section is a groove 7 and each groove 80 is arranged in the face of each section opposite to that to which the hinge is connected, and slidably mounted within this groove is a locking member comprising a sliding blade 8. One end of this blade 8 is adapted to rest 85 within the alining groove 9 formed within the adjacent section. The top section may be provided with a suitable knob or handle 10 of any desired or wellknown configuration, whereas the outer end of the lower section 90 is provided with a protecting nipple 11. The blades 4 may be secured and retained within the section by means of the rivets or pins 12. By so hingedly connecting the sections together they may be folded 95 in the position as shown in Fig. 2, thereby taking up a comparatively small amount of space and permitting same to be folded in a small package.

When it is desired to open the cane so as 100 to present it in its extended position as shown in Fig. 1, the sections may be swung upon their hinged connections and the blades 4 will enter the grooves 5, thereby forming substantially a single rigid stick, 105 and to prevent the sections from swinging upon their hinged connections the locking blades 8 may be moved along so as to be seated within the recesses 9, whereby the sections will be held in an extended position 110 to provide a single stick suitable for use when walking. When it is desired the user

may release the locking members by sliding the blades 8 back within the recesses 7 and folding the sections upon one another, whereby they will be folded in a compact package, so that the cane will take up a comparatively small amount of space when not in use.

Whereas I have illustrated in the drawings a sliding blade 8 as a locking member it is of course to be understood that any suitable locking members may be used for locking the sections in open position.

Having thus fully described my invention, what I claim as new and desire to secure by Letters Patent is:

A cane of the character described, comprising a plurality of sections, hinges con-

necting said sections together, the said hinges being so arranged that the adjacent sections may be folded one upon the other, a blade extending from one end of each section, the opposite end of each section having recesses therein for receiving said blades, registering grooves formed in the ends of each section, and locking members slidably mounted in one of said grooves and engaging in the opposing section groove for locking said sections in open position.

In witness whereof I have hereunto set my hand Feb. 24th, 1919.

FRANK KUTWICZ.
